GAS MASK CARRIER POCKET ATTACHMENT
FOR FIREMEN'S COATS

Alfred M. Grunwell, Washington, D. C.

Application February 10, 1945, Serial No. 577,319

7 Claims. (Cl. 128—144)

1
The present invention relates to improvements in garments and has reference more particularly to a pocket attachment to a fireman's "turn-out-coat" for housing a gas mask and its associated air purifying canister.

At the present time the gas masks and associated air purifying canisters now generally used by firemen are normally stored in a suitable container provided therefor on the fire apparatus.

It has been found from experience upon reaching the scene of a fire, that in order to gain access to the gas or smoke filled area with safety and protection from the smoke and noxious gases, the fireman must return to the fire apparatus which is usually located a considerable distance from the scene of the fire and obtain one of the gas mask units and upon donning the gas mask and its supporting harness, he then returns to the point where the gas mask is needed so that he can enter the smoke or gas filled area without inhaling any of the injurious gases. This loss of time very frequently results in the loss of life in enabling entrapped victims to be rescued.

It is, therefore, the primary object of my invention to provide means on the "turn-out-coat" usually worn by a fireman for housing the gas mask and its associated air purifying canister so that the gas mask will at all times be quickly and readily accessible to the wearer, thereby saving considerable time in enabling a fireman to apply the gas mask and enter the smoke or gas filled area whenever the occasion necessitates the use of a gas mask.

Another object of importance of the present invention resides in the provision of a gas mask carrier pocket attachment for firemen's "turn-out-coats" that will obviate the necessity of having to employ the usual supporting harness for the gas mask when the latter is in use, means being provided in the carrier pocket attachment for supporting the air purifying canister in a fixed, yet detachable manner.

Still a further object resides in arranging the gas mask carrier pocket on the fireman's "turn-out-coat" in such a manner as not to cause any interference with the use of the usual fire fighting equipment, such as the water hose, axe, pick, and at the same time protect the air purifying canister from coming in contact with any fouling medium, such as water.

Also, the invention aims to so arrange the gas mask carrier pocket on the garment as not to cause any discomfort to the wearer while seated on the fire apparatus in going to the scene of the fire.

2
Another and important object is to provide a gas mask carrier pocket attachment that can be either sewed onto the fireman's "turn-out-coat" or formed as a separate unit that can be readily and easily attached to or removed from the coat.

Other objects and advantages will become apparent from the following description when taken in connection with the accompanying drawings.

10 In the drawings forming a part of the specification and in which like reference characters designate corresponding parts throughout the several views:

Figure 1 is a front elevation of a fireman's 15 "turn-out-coat" showing the gas mask carrier pocket attached thereon;

Figure 2 is a rear elevation;

Figure 3 is an enlarged fragmentary view of the carrier pocket showing the manner in which 20 the air purifying canister is supported in the pocket;

Figure 4 is a sectional view taken approximately on the line 4—4 of Figure 3 looking in the direction of the arrows and showing the canister supporting means in top plan;

Figure 5 is a vertical sectional view taken approximately on the line 5—5 of Figure 3 looking in the direction of the arrows;

Figure 6 is an elevational view of the pocket 30 looking from the open rear side thereof;

Figure 7 is a detail perspective view of a modification of the carrier pocket wherein the same comprises a separate unit adapted for detachable connection with the coat;

Figure 8 is a vertical sectional view showing 35 the manner in which the separate carrier pocket is attached to the coat; and

Figure 9 is a detail perspective view of one type of canister supporting member.

40 In the drawings, the numeral 1 designates a conventional fireman's "turn-out-coat." Sewed to the back and extending around one side and toward the front of the coat is my improved carrier pocket denoted generally by the numeral 2.

45 This pocket is formed from pieces of material similar to that of which the coat is made and comprises a front wall 3, top and bottom walls 4 and 5 and a rear end wall 6. These walls are stitched together and the inner marginal edge portions 6 and 7 of the top and bottom walls, as well as the inner marginal edge portion 9 of the end wall 6 are stitched to the "turn-out-coat" 1, as is clearly indicated at 10 on the drawings.

50 The pocket 2 extends substantially horizontally

across the back of the coat directly above the waistline and the forward end portion of this pocket extends around the side of the coat and terminates at the front of the coat, as clearly illustrated in Figure 1.

A closure flap 11 is provided for the open forward end of the pocket and complementary fastening means 12 and 13 are associated with this flap 11 and the adjacent portion of the front wall 3. The fastening means may be in the nature of a snap fastener or "zipper." This flap is stitched along its rear vertical edge to the coat 1 at the juncture of the top and bottom walls 4 and 5 of the pocket.

As will be more readily observed from an inspection of Figures 2, 3 and 6 of the drawings, the closed rear end portion of the pocket is enlarged.

Also, the bottom of the enlarged rear portion of the pocket is open as indicated at 14 in the drawings and the purpose of this construction will be readily apparent in due course.

A gas mask (not shown) of the conventional construction has the usual flexible hose 15 affording communication with the top of an air purifying canister 16, also of the usual construction. This canister contains the necessary chemicals and filter to extract poisonous and irritating dusts and gases from the air. The canister is provided with an air inlet opening in its bottom and this air inlet opening is normally sealed against the admission of air by means of a piece of adhesive tape 17, one end of which extends outwardly of the opening 14 in the pocket to provide a pull tab 18 to facilitate its quick and easy removal from over the air inlet opening in the bottom of the canister when the gas mask is to be used.

Forming an important part of the present invention is the means arranged in the pocket to support the air purifying canister in proper position in the enlarged portion of the pocket.

To this end, I provide the bands 19 and 20 that are stitched along their inner ends to the back of the coat as at 21. These bands overlap at their outer free ends and suitable fasteners 22 are associated with the overlapping ends of the bands to secure them together in position around the canister 16.

Supporting straps 23 and 24 are associated with the bands 19 and 20 respectively for engagement with and to support the bottom of the canister 16, in the manner as is clearly shown in the drawings.

The canister 16, will thus be supported in a vertical position in the enlarged rear end portion of the pocket with its air inlet end disposed directly over the opening 14 in the bottom wall 5 of the pocket and with the adhesive tape projecting outwardly of this opening 14.

The flexible hose 15 will be collapsed and maintained in the pocket and also the gas mask connected to the forward end of this hose will be concealed in the forward end portion of the pocket.

In Figure 7 of the drawings, I have illustrated a modification of the carrier pocket, wherein the same comprises a separate unit that can be readily and easily attached and removed from a fireman's "turn-out-coat."

In this form the pocket 25 includes a front wall 26, a rear wall 27, top and bottom walls 28 and 29 and rear end wall 30, stitched together. The rear end portion of this pocket is enlarged similar to enlarged rear portion of the first men-

tioned form of pocket construction. Likewise, the forward end of this modified pocket is open and a closure flap 31 forming an extension of the rear wall 27 is provided for the open forward end of this pocket 25. Complementary fastening means 32 and 33 are associated with the flap 31 and the front wall 26 to retain the flap in a closed position.

Tabs 34 extend laterally from the edges of the rear wall 27 at spaced intervals and carried by these tabs are suitable snap fastener elements 35 that cooperate with complementary fastener elements 36 attached to adjacent portions of the coat 1.

In lieu of snap fasteners any other well known type of detachable fastening means may be employed for detachably securing the carrier pocket onto the coat.

The air purifying canister may be removably supported in the enlarged rear end of this pocket 25 in the same manner as the canister is removably supported in the pocket 2.

In Figure 9 a modification of the canister support is disclosed wherein a single band 37 has its intermediate portion stitched or otherwise secured in the rear portion of the pocket. The free ends of this band overlap and have fasteners 38 associated therewith to secure the band around the canister. Supporting straps 39 are associated with the lower edge of the band to engage with and support the bottom of the canister.

In some instances, instead of arranging the pocket across the back of the coat, it may be desirable to mount the pocket at the side of the coat and beneath one of the sleeves.

With a device of this character, the fireman will at all times have his gas mask carried by the "turn-out-coat" and thus the gas mask can be readily and easily put into use wherever the occasion arises, thus saving considerable time and furthermore obviating the necessity of having to employ a special harness to support the air purifying canister. Also, with my improved device, the carrier pocket will in no way interfere with the use of the fire fighting equipment by the user.

A carrier pocket of the above mentioned character can be readily and easily attached to a fireman's "turn-out-coat" and will, furthermore, be inexpensive, strong and durable.

While I have shown the preferred embodiment of my invention, it is to be understood that various changes in the size, shape and arrangement of parts may be resorted to without departing from the spirit of the invention and the scope of the appended claims.

Having thus described the invention, what I claim is:

1. In combination with a coat; a carrier pocket for a respiratory apparatus forming a part of the coat, the respiratory apparatus including an air purifying canister and a flexible hose for delivering purified air to a gas mask from the canister, said pocket serving as a support for the canister when the respiratory apparatus is in use, and adapted to entirely contain the aforesaid parts of the respiratory apparatus when the latter is not in use.

2. In combination with a coat; a carrier pocket for a respiratory apparatus forming a part of the coat, the respiratory apparatus including an air purifying canister and a flexible hose for delivering purified air to a gas mask from the canister, means for detachably securing and supporting the canister in the pocket, said pocket entirely receiving and concealing all of the parts

5

of the respiratory apparatus when the latter is not in use.

3. The combination with a garment and a respiratory apparatus including an air purifying canister and a flexible hose for conducting purified air from the canister to a gas mask; of a carrier pocket forming a part of the garment and arranged across the back of the garment, said pocket adapted to entirely receive all of the parts of the respiratory apparatus when the latter is not in use, and further serving as a support for the canister when the respiratory apparatus is in use.

4. The combination with a garment and a respiratory apparatus including an air purifying canister, and a flexible hose for conducting purified air from the canister to a gas mask; of a carrier pocket forming a part of the garment and arranged across the back of the garment and extending around the side thereof and to the front of the garment, the front end of the pocket being open, and a closure flap for the open end of the pocket, said pocket adapted to entirely receive all of the parts of the respiratory apparatus when the latter is not in use, and further serving as a support for the canister when the respiratory apparatus is in use.

5. The combination with a garment and a respiratory apparatus including an air purifying canister, and a flexible hose for conducting purified air from the canister to a gas mask; of a carrier pocket forming a part of the garment and arranged across the back of the garment, said pocket adapted to entirely receive all of the parts of the respiratory apparatus when the latter is not in use, and further serving as a support for the canister when the respiratory apparatus is in use, means for securing and supporting the canister in one end portion of the pocket, said end portion of the pocket being provided with an opening to admit air to the canister, said canister having an air inlet in registration with the air opening in

6

the pocket, and a removable seal normally covering the air inlet in the canister and having a free end extending through the opening in the pocket and accessible from the exterior of said pocket.

5. 6. In combination with a fireman's turn-out-coat; a carrier pocket for a respiratory apparatus forming a part of the coat, the respiratory apparatus including an air purifying canister, and a flexible hose for delivering purified air to a gas mask from the canister, said pocket adapted to entirely receive all of the parts of the respiratory apparatus when the latter is not in use, and means for securing and supporting the canister within the pocket, said means comprising a band secured within the pocket and embracing the canister, loop members depending from the band and engaging the bottom of the canister, said pocket having an opening provided in one wall thereof to admit air to the canister.

7. In combination with a fireman's turn-out-coat; a carrier pocket for a respiratory apparatus forming a part of the coat, the respiratory apparatus including an air purifying canister, and a flexible hose for delivering purified air to a gas mask from the canister, said pocket adapted to entirely receive all of the parts of the respiratory apparatus when the latter is not in use, and means for securing and supporting the canister within the pocket, said means comprising a band secured within the pocket and embracing the canister, loop members depending from the band and engaging the bottom of the canister, said pocket having an opening provided in the bottom thereof to admit air to the canister, the bottom of the canister having an air inlet in registration with the air opening, a removable seal normally covering the air inlet in the canister, and a pull tab carried by the seal and extending through the air opening in the bottom of the pocket for access 30
